VALVE MEMBER

Gilbert Schwartzman, New York, N.Y., assignor to
Dab-O-Matic Corporation

Filed Feb. 6, 1968, Ser. No. 10,465

Term of patent 14 years

Int. Cl. D23—01

U.S. Cl. D23—19

FIG. 1

FIG. 2

FIG. 3

FIG. 4

FIG. 1 is a front perspective view of a valve member showing my new design, the rear view being identical;

FIG. 2 is a side elevational view thereof, the opposite side being identical;

FIG. 3 is a top plan view thereof; and

FIG. 4 is a bottom plan view thereof.

I claim:

The ornamental design for a valve member, as shown and described.
